DU PONT DE NEMOURS POWDER COMPANY, OF WILMINGTON, DELA-
WARE, A CORPORATION OF NEW JERSEY.

APPARATUS FOR IGNITING PRIMERS IN WELLS.

No. 839,194.

Specification of Letters Patent.

Patented Dec. 25, 1906.

Application filed November 8, 1906. Serial No. 342,470.

To all whom it may concern:

Be it known that I, FRANCIS I. DU PONT, a citizen of the United States, residing at Wilmington, county of Newcastle, and State of Delaware, have invented a new and useful Improvement in Apparatus for Igniting Primers in Wells, of which the following is a full, clear, and exact description, reference being had to the accompanying drawing, which forms a part of this specification.

By my invention, as I will hereinafter specifically show, the fuse is subjected to an intensely hot atmosphere of gases under pressure for a considerable period, which insures the ignition of the fuse. I accomplish this, speaking generally, by using a comparatively slow burning composition and sealing or confining the gases in contact with the fuse until the pressure rises sufficiently above that, due to the depth of the well, to rupture the seal. Thus the fuse is kept in contact with hot gases for a considerable period of time to positively insure its ignition. Further, I place the ignition-wires in a tube, which is also held by this seal, so that when the seal is broken the tube, with the ignition-wires, may be removed for further use.

I will first describe the embodiment of my improvement, which is shown in side elevation, partially in section, in the accompanying drawing.

In the drawing, *k* is the fuse-case, having the fuse *p* therein. At the bottom of the fuse-case is the steel disk *g*, having a central opening through which the fuse *p* passes to the primer *s*.

r is a rubber packing.

At the upper end of fuse *p* is a steel disk *o*, having a central orifice through which projects the upper end of fuse *p*. The end of this fuse is in close proximity to the ignition-powder or charge *l*, which is confined in the cylinder *m*. This ignition-powder is placed in the tube *b*, in which are the wires *a a*, leading from a source of current-supply and connected at the ignition charge by resistance *i*. Surrounding, but not in contact with, the ignition-powder *l* is a ring *n* of smokeless powder. Above this ring *n* and surrounding tube *b* is a tube *g* of smokeless powder, having the longitudinal openings *f*. Surrounding the disk *o*, the ring *n*, and the tube *g* is the iron pipe *e*, the lower end of the pipe be-

ing surrounded by the upper end of fuse-case *k*.

c is an iron pipe pressed tightly against pipe *e* and having an orifice through which tube *b* passes, rubber packing *d* closing the opening between tube *b* and pipe *c* and closing the upper end of the chamber in which the ignition and smokeless powders are placed. It is of sufficient strength to prevent rupture at the pressure of the well at the depth where the explosion is designed to take place. The interior of chamber *b* is filled with rosin.

The operation is as follows: If, for instance, the depth at which the fuse is placed is such that the outside pressure on the apparatus is, say, five hundred pounds, the chamber in which is the powder being sealed, the internal pressure is that of the atmosphere. Electric current being passed through the wires *a a* and resistance *i*, the ignition-powder *l* and ring *n* are ignited. The flame from this ignition-powder and ring passes up through openings *f* in block *b*, creating a combustion throughout the cylinder *g*. This cylinder is of slow-burning powder. During the burning of cylinder *g* it is evolving gases, which are held from escaping by seal *d*, and the pressure increases until it reaches a point high enough above that of the outside pressure to rupture the packing *d*. This, however takes an appreciable time, and during that time the fuse *p* is subjected to the action of the flame and of the intensely-hot atmosphere of the gases, thus positively insuring the ignition of the fuse. When the packing *d* is ruptured, the tube *b*, with the wires, may be removed and again used.

Having now fully described my invention, what I claim, and desire to protect by Letters Patent, is—

1. In an apparatus for firing wells, in combination, a fuse, a chamber provided with a rupturable seal, slow-burning powder in said chamber, the fuse extending into said powder-chamber, and means to ignite said powder whereby the fuse is subjected to the flame and heated gases until the pressure produced is sufficient to rupture the seal.

2. In an apparatus for firing wells, in combination, a fuse, a tube, ignition-wires in said tube, a chamber provided with a rupturable seal surrounding said tube, slow-burning

- powder in said chamber, the fuse extending into said powder-chamber whereby the fuse is subjected to the flame and heated gases and the ignition-wire tube held in place until the pressure produced is sufficient to rupture the seal.
3. In an apparatus for firing wells, in combination, a fuse, a chamber provided with a rupturable seal, powder in said chamber, the fuse extending into said powder-chamber, and means to ignite said powder whereby the fuse is subjected to the flame and heated gases until the pressure produced is sufficient to rupture the seal.
4. In an apparatus for firing wells, in combination, a fuse, a tube, ignition-wires in said tube, a chamber provided with a rupturable seal surrounding said tube, powder in said chamber, the fuse extending into said powder-chamber whereby the fuse is subjected to the flame and heated gases and the ignition-wire tube held in place until the pressure produced is sufficient to rupture the seal.
5. In an apparatus for firing wells, in combination, a fuse, a chamber provided with a rupturable seal, a powder-block in said chamber having longitudinal openings, said fuse extending into said powder-chamber, and means to ignite said powder.
6. In an apparatus for firing wells, in combination, a fuse, a chamber provided with a rupturable seal, a slow-burning powder-block in said chamber having longitudinal openings, said fuse extending into said powder-chamber, and means to ignite said powder.
7. In an apparatus for firing wells, in combination, a fuse, a tube, ignition-wires in said tube, a chamber provided with a rupturable seal, surrounding said tube, a powder-block in said chamber having longitudinal openings, the fuse extending into said powder-chamber.
8. In an apparatus for firing wells, in combination, a fuse, a tube, ignition-wires in said tube, a chamber provided with a rupturable seal, surrounding said tube, a slow-burning powder-block in said chamber having longitudinal openings, the fuse extending into said powder-chamber.
9. In an apparatus for firing wells, in combination, a fuse, a chamber provided with a rupturable seal, slow-burning powder in said chamber, the fuse extending into said powder-chamber, ignition-powder, and means to ignite said powder.
10. In an apparatus for firing wells, in combination, a fuse, a chamber provided with a rupturable seal, powder in said chamber, the fuse extending into said powder-chamber, ignition-powder, and means to ignite said powder.
11. In an apparatus for firing wells, in combination, a fuse, a tube, ignition-wires in said tube, ignition-powder adapted to be ignited by said wires, a chamber provided with a rupturable seal, surrounding said tube slow-burning powder in said chamber, the fuse extending into said powder-chamber whereby the fuse is subjected to the flame and heated gases and the ignition-wire tube held in place until the pressure produced is sufficient to rupture the seal.
12. In an apparatus for firing wells, in combination, a fuse, a tube, ignition-wires in said tube, ignition-powder adapted to be ignited by said wires, a chamber provided with a rupturable seal, surrounding said tube powder in said chamber, the fuse extending into said powder-chamber whereby the fuse is subjected to the flame and heated gases and the ignition-wire tube held in place until the pressure produced is sufficient to rupture the seal.
13. In an apparatus for firing wells, in combination, a fuse, a chamber provided with a rupturable seal, a powder-block in said chamber having longitudinal openings, said fuse extending into said powder-chamber, ignition-powder and means to ignite said ignition-powder.
14. In an apparatus for firing wells, in combination, a fuse, a chamber provided with a rupturable seal, a slow-burning powder-block in said chamber having longitudinal openings, said fuse extending into said powder-chamber, ignition-powder and means to ignite said ignition-powder.
- In testimony of which invention I have hereunto set my hand, at Wilmington, on this 5th day of November, 1906.

FRANCIS I. DU PONT.
